J. S. ALLEN.

TRAIN SIGNAL APPARATUS.

APPLICATION FILED FEB. 12, 1913.

1,132,418.

Patented Mar. 16, 1915.

THE NORRIS PETERS CO., PHOTO-LITHO., WASHINGTON, D. C.

UNITED STATES PATENT OFFICE.

JUDGE SHIRLOCK ALLEN, OF NEW YORK, N. Y.

TRAIN-SIGNAL APPARATUS.

1,132,418.

Specification of Letters Patent. Patented Mar. 16, 1915.

Application filed February 12, 1913. Serial No. 747,864.

To all whom it may concern:

Be it known that I, JUDGE S. ALLEN, a citizen of the United States, and a resident of the city of New York, borough of Manhattan, in the county and State of New York, have invented a new and Improved Train-Signal Apparatus, of which the following is a full, clear, and exact description.

My invention has for its object to provide a train signal apparatus, in which the signal is thrown into danger position by mechanism operable by a weight when a train is on a certain section of the track, the weight being raised by a motor, when the train reaches the said section of the track, to throw the signal into safety position.

Another object of the invention is to provide means for stopping the motor, and for holding the weight raised when the motor has raised the weight to a predetermined height.

Still other objects of the invention will appear in the following complete specification, in which the preferred form of the invention is disclosed.

In the drawings similar characters of reference indicate corresponding parts in all the views, in which—

Figure 1 is an elevation, showing the signal post, parts being broken away, to show the means provided for operating the signal post; Fig. 2 is a sectional view on the line 2—2 of Fig. 1; Fig. 3 is an enlarged fragmentary view, showing the means provided for holding the weighted arm in position; Fig. 4 is an enlarged fragmentary view, showing the means for cutting out the motor when the weighted arm has been raised to normal position; Fig. 5 is a fragmentary view showing the roller on the weighted arm, with which the pivoted hook engages; and Fig. 6 is a diagrammatic view, showing the method of wiring.

By referring to the drawings it will be seen that a hollow post 5 is provided, which is disposed on a base 6, which rests on a casing 7, this casing 7, if desired, being disposed below the level of the ground. In the hollow post 5 there is journaled a vertical shaft 8, the lower terminal 9 of this vertical shaft 8 being journaled in a bearing 10 in a standard 11. Secured to the shaft 8 there is a beveled gear 12, with which meshes a bevel gear 13, secured to a shaft 14, journaled in a bearing 15. There is also secured to this shaft 14, a gear wheel

16, with which meshes a gear wheel 17, secured to a shaft 18, journaled in a bearing 19, in a standard 20. There is also secured to this shaft 18 a gearing 21, with which meshes a gear 22, secured to the shaft 23, of the electric motor 24. It will therefore be seen that this motor 24 by the gear wheels set forth is adapted to rotate the shaft 8 to which the signal means, which will be hereafter described, is secured. Secured to the shaft 14 there is an arm 25, having a weight 26 at its terminal, this arm 25, with its weight, serving to rotate the shaft 14, and by means of the beveled gears 13 and 12, 70 rotate the shaft 8, so that the signal means mounted on the said shaft 8 may be moved to danger position, when the said weighted arm 25 is free to rotate the said shaft 14.

As a means for holding the weighted arm 75 upward, I provide a hook member 27, which is adapted to engage a roller 28, which is journaled in brackets 29, secured to the underside of the weighted arm 25. This construction is shown in Fig. 5 of the drawings. The hook member 27 is pivoted at 30 to a bracket 31, and pivoted to the hook member 27 there is an armature 32, the movement of the armature 32 relatively to the hook member 27 being limited by the 80 stops 33, which are secured to the said hook member 27. However, it will be understood that the armature 32 has a slight movement relatively to the hook member 27, so that when the armature 32 falls, it will jar the 85 hook member 27 free from the roller 28. The armature 32 is adapted to be held in the position shown in Fig. 2 of the drawings by the magnet 34.

By referring to Fig. 6 of the drawings, it 90 will be seen that a track 35 has two rails 36 and 36^a, and that a battery or other source of electric energy is connected by the wire 38 with one of the rails 36, and by the wire 39 with the other rail 36^a. It will also be 100 seen that the wire 40 connects the rails 36^a with the magnet 34, a resistance 41 being connected with the wire 40, between the rail 36^a and the said magnet 34. It will also be seen that a wire 42 connects the magnet 34 105 with the motor 24, and the wire 44 connects the other pole of the motor 24 with the rail 36. The section 35 of the track is insulated at 45 from the remainder of the track, and when there are no cars in the said section 35 of the track, and no other short circuit between the rail 36 and the rail 36^a, the 110

current will pass from the battery, or other source of electric energy, through the rail 36^a, through the resistance 41, the magnet 34, the switch 47, the wire 44, the rail 36, the wire 38 to the battery 37. This will energize the magnet 34 and hold the armature 32 upward with the hook member 27 engaging the roller 28, to hold the weighted arm 25 upward. This will hold the signal means to be hereafter described, in safety position, but when a car passes on the rails 36 and 36^a on the section 35 of the track, the resistance 41 will prevent the current from passing to the magnet 34, and the current will pass from the battery, or other source of electrical energy, through the wire 39 to the rail 36, across the axle 46, from the rail 36^a to the rail 36, and back to the wire 38. This will free the armature 32 from the influence of the magnet 34, and as the armature 32 falls, its slight movement relatively to the hook member 27 will jar the hook member 27 so that it will free itself from the roller 28, and permit the weighted arm 25 to fall. This fall of the weighted arm 25 will rotate the shaft 8, to which the signal means are secured. When the weighted arm 25 falls, the switch 47 will be free to fall and open the short circuit through the switch 47 and around the motor 24 so that when the car having the axle 40 leaves the section 35 of the track, the short circuit made by the said axle will be removed, and the current will pass through the resistance 41, the magnet 34, to operate the motor 24. This motor 24 will by the means described, rotate the shaft 8 and raise the weighted arm 25 for engagement of the roller 28 on the weighted arm 25 by the hook member 27. When the weighted arm 25 is raised, the armature 32 will be held by the influence of the magnet 34 to retain the hook member 27 in position for supporting the weighted arm 25. When the weighted arm 25 reaches its uppermost position, it will press up the switch 47, to short circuit the motor 24, as will be seen by referring to the diagrammatic view, shown in Fig. 6. The current flowing to the motor energizes the magnet and when the hook member 27 is returned to normal position, after being pushed aside by the upward passage of the weighted arm 25 the armature 32 will be held by the magnet 34. In this way the magnet 34 will, by means of the armature 32, hold the hook member 27 in position to retain the weighted arm 25 in its uppermost position, until another car, having an axle 46, passes into the section 35 of the track, when the current will again be short circuited by the said axle 46, to deenergize the magnet 34, and permit the weighted arm 25 to again fall. The switch 47 is shown in detail in Fig. 4, the dotted lines showing the position of the switch when it is raised to short circuit the motor.

Secured to the shaft 8 there is a cap or hood 64, this cap or hood 64 having a top 65. The sides 68 of this hood 64 diverge downwardly a considerable distance with their lower portion 69 forming an apron. Secured to the top 65 of the hood 64 there is a signal blade 77, this signal blade 77 extending from one side of the hood 64, an arm 78 being provided, which is also secured to the top 65 of the hood 64, this arm 78 extending from the other side of the hood. This arm is provided for engaging a member on the cab of a locomotive, for operating any approved mechanism thereon, for sounding a signal, applying the brakes, or cutting off the power in the locomotive.

By reference to Fig. 6 of the drawings, it will be seen that when the current is not short circuited, the current will energize the magnet 34, to hold the weighted arm 35 raised, and when in this position the signal blade 77 and the arm 78 will be disposed substantially parallel with the track. However, when a train runs into the section 35 of the track, the current will be short circuited, and the magnet 34 will be deenergized, which will permit the arm 25 to fall, to rotate the shaft one quarter revolution, which will move the signal blade 77 and the arm 78 at right angles to the track.

When the train which has moved into the section 35 of the track leaves the said section, the current will again energize the magnet 34, and will operate the motor, as the switch 47 has been permitted to fall when the weighted arm 25 moved downward. This motor 24 will therefore raise the weighted arm 25, which will short circuit the motor, as has been explained, the weighted arm 25 being held in position by the action of the magnet 34 on the armature 32, until the current is again short circuited by the movement of the train into the section 35 of the track.

Having thus described my invention, I claim as new and desire to secure by Letters Patent:

1. In a train signal apparatus, a signal means, a weight for moving the signal means in one direction, a motor for moving the signal means in the opposite direction, a pivoted hook depending from its pivot and positioned for engaging and supporting the weight under normal conditions, an armature carried by the hook, a magnet for attracting the armature, a circuit connecting the magnet and the motor, and a switch in the circuit operable by the weight.

2. In a train signal apparatus, a signal, a shaft, means connecting the shaft with the signal for operating the latter, a weighted arm secured to the shaft, electrically operated means for raising the weighted arm, a pivoted hook depending from its pivot in position for engaging the weighted

arm, an armature pivoted to the hook, stops for limiting the movement of the armature relatively to the weighted arm, and a magnet for attracting the armature.

5 3. In a train signal apparatus, a signal, a shaft, means connecting the shaft with the signal for operating the latter, a weighted arm secured to the shaft, electrically operated means for raising the weighted arm, 10 a hook normally engaging the weighted arm, an armature on the hook, a magnet for attracting the armature, a circuit connected with the motor, and a pivoted switch in the circuit and disposed in the path of the 15 weighted arm to open the circuit by the upward movement of the weighted arm.

4. In a train signal apparatus, a signal, a shaft, means by which the shaft is adapted for operating the signal, a weighted arm 20 secured for rotating the shaft, a hook for engaging and holding the arm in raised position, an armature pivoted to the hook and having a limited movement relatively

thereto, and a magnet for holding the armature with the hook in operative position. 25

5. In a train signal apparatus, a signal, means for operating the signal, a weighted arm connected for moving with the means, a motor for operating the means, a pivoted hook engaging the arm, an armature pivoted 30 to the arm and having a limited movement relatively thereto, a magnet for coöperating with the armature for holding the hook in operative position, wires connecting the motor and the magnet for operating the 35 motor and energizing the magnet, and means for cutting off the current to the motor when the arm is in raised position.

In testimony whereof I have signed my name to this specification in the presence of 40 two subscribing witnesses.

JUDGE SHIRLOCK ALLEN.
